UNITED STATES PATENT OFFICE.

OVAL L. DILLON, OF BLOOMINGTON, ILLINOIS, ASSIGNOR OF ONE-THIRD TO ARTHUR C. FUNK AND ONE-THIRD TO LAWRENCE F. FUNK, BOTH OF SHIRLEY, ILLINOIS.

WRENCH.

1,171,328.

Specification of Letters Patent.

Patented Feb. 8, 1916.

Application filed November 12, 1914. Serial No. 871,682.

To all whom it may concern:

Be it known that I, OVAL L. DILLON, a citizen of the United States, residing at Bloomington, in the county of McLean and 5 State of Illinois, have invented certain new and useful Improvements in Wrenches, of which the following is a specification.

The present invention relates to a wrench more particularly adapted to be used by 10 mechanics, etc., for the usual purposes to which the ordinary wrench is applied.

The objects of the present invention are to so construct the head of the wrench as to permit the jaws thereof to be turned and 15 placed in any relative position of angularity desired with respect to the handle.

A further object of the invention is to provide means whereby the space between the jaws may be varied to permit application 20 of the wrench to objects of various size.

Further objects of the invention are to provide means for locking the jaws in adjusted position and to provide means for locking the head in turned position.

25 The invention further consists in the features of construction and combinations of parts hereinafter described and claimed.

In the drawings: Figure 1 is a side view partly in section of the wrench of the present invention showing by means of dotted and full lines the head turned to bring the jaws into different positions of angularity with respect to the handle and the jaws moved different distances apart to adjust the 35 spacing therebetween; Fig. 2 is a plan view of the parts shown in Fig. 1; Fig. 3 is a face view of that portion of the head carrying the fixed jaw; and Fig. 4 is a face view of that portion of the head carrying the 40 movable jaw.

In the construction of the common form of wrench the head maintains a fixed position with respect to the handle and it is sometimes difficult, owing to its location, to 45 gain a purchase upon the nut or other article being operated upon. In the type of wrench illustrated in the present application, the above difficulty is overcome by making the head so that it can be turned into angular 50 position with respect to the handle. In order to make the wrench applicable for use upon various sized articles, it is frequently necessary to change or adjust the distance which the jaws are spaced apart,

and the present invention deals with a means for accomplishing this end in conjunction with that type of wrench in which the head can be turned.

Referring to the drawings, the wrench consists of a handle 5 of any suitable shape 60 or size which terminates at its upper end in a fork 6 and mounted within this fork by means of a pin 6^a, is the head 7 consisting of a part 8 and a part 9. The part 8 carries what may be termed the movable 65 gripping jaw 10, and the part 9 carries what may be termed the fixed gripping jaw 11. The part 8 is formed for a major portion of its periphery with teeth 12 and the part 9 is formed with teeth 13 similar to the teeth 70 12, and also with teeth 14 which slope in an opposite direction from the direction of slope of the teeth 12 and 13. The teeth 12 and 13 are designed to aline with one another when the device is assembled and arranged to engage with said teeth is a spring-pressed pawl 15 mounted in the handle 5 (see Fig. 1). The handle is formed with a slot 16 through which extends a finger piece 17 for moving the pawl 15 to bring it out of 75 engagement with the teeth 12 and 13. It is obvious from the drawings that by releasing this pawl 15 the head is free to be turned to any desired position by releasing the finger piece 17 the spring of the pawl will 80 act to force the pawl back into place and lock the head in turned position, so that by this means the head can be adjusted to any 85 position of angularity with respect to the handle. 90

As stated, it is necessary for practical use of the wrench to adjust the spacing between the jaws and for this purpose one of the jaws carries a spring-pressed pawl 18 which is adapted and arranged to engage with the 95 teeth 14 of the head 9 and a suitable finger piece 19 is provided for raising and lowering this pawl. Thus by turning the part 8 or part 9 and dropping this pawl into any of the teeth 14 desired it is obvious that the 100 spacing between the jaws can be regulated. By arranging the teeth 14 so that they slope in an opposite direction from the direction of slope of the teeth 12 and 13, the jaws cannot open up or spread apart while the 105 wrench is being used, and the teeth 14 being spaced apart a distance equal to the distance between the teeth 12 or 13 adjustment of the

jaw 10 by turning of the part 8 or 9 of the head does not place the teeth 12 and 13 out of alinement.

The terms fixed and movable jaws are used for descriptive purposes only, since both are in fact fixedly secured to that portion of the head with which they are associated.

By the above construction the head of the wrench can be turned to angularly adjust the jaws with respect to the handle, and the jaws can be relatively adjusted so as to vary the space therebetween and by these adjustments the wrench can be arranged to operate upon objects of different sizes and objects placed in a position which it would be difficult, if not impossible, to operate upon with that style of wrench in which the head is fixed with respect to the handle.

The device is extremely cheap of construction and contains no involved parts which would become impaired by ordinary usage.

I claim:

1. In a wrench the combination of a handle, a head carried by said handle and adapted to be turned into different degrees of angularity with respect to said handle, said head consisting of two parts independently movable about a common center, a jaw extending from each of said parts, the periphery of said parts being formed with teeth, means for engaging said teeth to lock the

head in turned position, a portion of the teeth on one of said parts sloping in an opposite direction from the direction of slope of the remaining teeth, a shiftable member carried by one of said jaws and adapted to engage with the oppositely sloping teeth for locking the jaws in adjusted position with respect to each other, substantially as described.

2. In a wrench the combination of a handle, a head carried by said handle and adapted to be turned into different degrees of angularity with respect to said handle, said head consisting of two parts independently movable about a common center, a jaw extending from each of said parts, the periphery of said parts being formed with teeth, means for engaging said teeth to lock the head in turned position, a portion of the teeth on one of said parts sloping in an opposite direction from the direction of slope of the remaining teeth, a shiftable member carried by one of said jaws and adapted to engage with the oppositely sloping teeth for locking the jaws in adjusted position with respect to each other, and all of said teeth being spaced apart an equi-distance, substantially as described.

OVAL L. DILLON.
